(57) **CLAIM**

The ornamental design for a combination cornhole game board and leisure chair, as shown and described.

DESCRIPTION

FIG. 1 is a front perspective view of the combination cornhole game board and leisure chair of my design wherein the pouch flap is open and folded back.

FIG. 2 is a rear perspective view thereof, wherein the pouch flap is closed.

FIG. 3 is a closeup view of the carry strap and the closure part of the game board-chair, wherein no pouch flap is shown.

FIG. 4 is a left side perspective view of the game board and chair of this design wherein the pouch flap is closed.

FIG. 5 is a right side perspective view with the back in position for a sitting person wherein the pouch flap is closed.

FIG. 6 is a a right side perspective view with the back tilted for game board use and play wherein the pouch flap is open and folded back.

FIG. 7 is a top closeup view of a portion of the chair seat and the attached pocket that holds the sacks for game playing, wherein the pouch flap is open and folded back.

FIG. 8 is a rear perspective view of the chair in a partially folded position with the sack pocket under the seat portion of the chair and no pouch flap is shown.

FIG. 9 is a front elevational view in a folded-up state showing the bag for holding game sacks in an external position wherein the pouch flap is closed.

FIG. 10 is a top view of a partially opened chair with game sack bag open wherein the pouch flap is open and folded upward.

FIG. 11 is a top perspective view of a partially open chair, showing the two parts of the parachute buckle closure to retain the chair in closed position and the sack pocket folded upwardly over the chair seat and has the pouch flap closed.

FIG. 12 is a top view of a closed chair showing the closure portions engaged and has the pouch flap closed.

FIG. 13 is closeup view of the direction flippable hook and loop closure pocket for the game sacks as disposed on the chair wherein the pouch flap is open and folded back.

FIG. 14 is a closeup view showing the hook and loop closure pocket that can flip over from the front to the back wherein the pouch pocket is open and folded back; and,

FIG. 15 is a detailed view showing the configuration of the carry handle flipped over to the front of the chair wherein no pouch flap is seen.

In the Figures set forth above, the smaller dashed lines represent stitching, whereas the longer dashed lines, are intended to convey non-claimed aspects.

1 Claim, 15 Drawing Sheets
